BALLPOINT PEN

Martienus K. P. Jonkers, Burgemeester Verheugstraat
49-55, Mierlo, Netherlands

Filed May 3, 1968, Ser. No. 11,767

Term of patent 14 years

Int. Cl. D19—06

U.S. Cl. D74—17

FIG. 1 is a front perspective view of a ballpoint pen showing my new design;

FIG. 2 is a top plan view;

FIG. 3 is a rear elevational view;

FIG. 4 is a side elevational view;

FIG. 5 is a front elevational view; and

FIG. 6 is an elevational view of the side opposite to that of FIGURE 4.

I claim:

The ornamental design for a ballpoint pen, substantially as shown.
